CLAIM

The ornamental design for a boat dryer, as shown and described.

DESCRIPTION

The patent or application file contains at least one drawing executed in color. Copies of this patent or patent application publication with color drawing(s) will be provided by the Office upon request and payment of the necessary fee.

1. Boat dryer

1.1 : Perspective

1.2 : Front

1.3 : Top

1.4 : Right

1.5 : Exploded

The parts in blue are not part of the claimed design.

1 Claim, 5 Drawing Sheets
(5 of 5 Drawing Sheet(s) Filed in Color)
